UNITED STATES PATENT OFFICE.

JOHN ERWOOD, OF CHICAGO, ILLINOIS.

WAREHOUSE-DOOR.

SPECIFICATION forming part of Letters Patent No. 788,761, dated May 2, 1905.

Application filed August 1, 1904. Serial No. 218,140.

To all whom it may concern:

Be it known that I, JOHN ERWOOD, a citizen of the United States, residing at Chicago, in the county of Cook and State of Illinois, have 5 invented new and useful Improvements in Warehouse-Doors, of which the following is a specification, reference being had to the accompanying drawings, forming a part thereof.

This invention relates to warehouse-doors, 10 and is designed as an improvement or modification of the warehouse-door shown in my application, Serial No. 149,959, filed March 28, 1903, now pending and allowed in the Patent Office.

15 It consists of the features of construction set out in the claims.

In the drawings, Figure 1 is a perspective view of my improved door shown at open position. Fig. 2 is a section at a vertical plane 20 transverse to the wall on which the door is hung, showing the door in edge elevation at nearly closed position. Fig. 3 is a plan view, on an enlarged scale, a portion of the door being broken away at the middle. Fig. 4 is a detail section of the guiding devices at the foot of the lower section of the door, section being made at the plane of the line 4 4 on Fig. 2. Fig. 5 is a detail section at the line 5 5 on Fig. 4. Fig. 6 is a detail side elevation of 25 the fitting and guiding devices at the foot of the lower section of the door, showing the door in elevated position. Fig. 7 is a detail section at the line 7 7 on Fig. 2.

This door is made in two sections, an upper 30 and a lower, hinged together at a longitudinal horizontal line, the lower section being preferably longer than the upper section by about the thickness of the door. The upper section is hinged to the horizontal bar 3, which is guided 35 on vertical rods 4, 4, rigidly mounted upon the wall in which is the doorway, which the door closes. Upon the upper side of said horizontal bar 3, approximately in line with each lateral edge of the door, there is mounted 40 a pulley 8, and to the ceiling or overhead support there are secured in line directly above said pulleys 8, 8, respectively, pulleys 9, 9. Adjacent to the pulley 9 at the left-hand side, and preferably, for convenience, journaled in 45 the same bracket, is a guide-pulley 9^a, and in

suitable position with respect to the pulley 9 at the right hand there is mounted a double-groove guide-pulley 10. At the opposite lateral edges of the lower section of the door, at the foot, there is mounted a tracking pulley 55 or wheel 11, for which a guide-track 12 is provided on the wall parallel with the vertical edge of the doorway. The pulleys 11 are preferably mounted in fittings 13, secured to the lower corners of the door. Each of the 60 lifting-cables 15 and 16 is connected at the lower ends to a link 14, which is pivoted to the corner-fitting 13 about midway in the thickness of the door and about as far from the lower edge as half said thickness, and the 65 link 14 has a lug 14^a projecting into a short vertical channel-bar 12^a, secured at the foot of the guide-rail 12, so that as the door approaches the floor it is engaged positively with the wall by the engagement of the lug 70 lug 14^a in the channel of the bar 12^a. The cable 15 at the right-hand side passes up along the edge of the door, through an aperture 17 in the plate 3, over the pulley 9, and thence down about the pulley 8 and up over the pulley 10 and thence down to the weight 18. The other cable, 16, passes up over the pulley 9 at the left-hand side of the door, down about the pulley 8 at that side, and thence up over the pulley 9^a, across above the door to 75 the other side, and over the pulley 10 in the second groove of the latter and down to the same weight 18. The weight 18 is designed to conventionally represent any necessary or convenient counterpoise for the doors. For 80 operating the door the axle of the double-groove pulley 10, at least one of whose grooves is adapted for driving engagement of the cable, has rigid with it a large working pulley 20, adapted in its groove for engagement of 85 an endless driving cable or chain 21, which extends down into convenient reach for an operator, who by means of it may rotate the pulley 20, and thereby the double-groove pulley 10, in either direction for operating the 90 door, supplying by hand the small deficiency of weight or counteracting the excess of weight of the counterpoise at different stages 95 of the door's movement. Except in details the construction above described is substan- 100

tially the same as that shown in my said application, Serial No. 149,959. With this construction, the door being suspended from the horizontal bar 3 at its hinge connection there-
5 with, the pivot-line of such hinge connection being at the outer surface of the door and the pivot-line of the hinge connection between the two sections being at the inner surface of the door, the door tends normally to hang
10 buckled slightly away from the wall or vertical plane in which its inner surface would stand when closed together perfectly at the hinge between the two sections; but a slight inward pressure will straighten the door and
15 thrust its lower edge down to the floor, and upon release the door would immediately buckle outward, the lower edge rising from the floor in such action, so that the operator by means of the chain 21 would readily lift
20 and fold it to elevated position, as seen in Fig. 1. In order to render the action of the door in closing fully at its lower position automatic, dispensing with the necessity for any assistance by the operator, I provide near the
25 upper end of each guide-track 12 a cam 23, which is in the form of an upwardly-open hook having an inclined face at the upper side. The upper door-section has projecting from each margin near the upper edge a pin
30 24, which is in position to overhang the inclined face of the cam-hook 23 as the door descends and to become engaged above and inward of the sloping upper face of said cam-hook. This engagement should occur after
35 the door has reached nearly its lowest position, the exact point varying with the weight and friction, in view of which the location of the pins may be selected by a little experiment with each size and weight of door, the differ-
40 ence being due to the varying effect of the friction of the operating devices and the weight of the door, upon the time in the descent of the door at which the bar 3 commences to descend, and the rate at which it
45 descends relatively to the descent of the lower edge of the lower section. When the pins become engaged behind the cam-hooks, as described, it will be seen that the further descent of the bar 3, carrying both sections of
50 the door down bodily, will cause the upper door-section to be drawn inward toward the wall by the slope of the cam-hooks with which the pins are engaged. For completing the straightening of the door by means of its
55 own descent—by gravity operating in excess of the counterpoise—I provide the lower door-section with a hook 25 at each lateral edge near the upper edge or hinge-line, such hooks being projected out laterally sufficiently to pass
60 beyond the lifting-cables and being then bent toward the wall, so as to travel alongside the guide-track 12. The downwardly-turned ends 26 of these hooks are sloped on the face away from the wall, so that engaging behind the
65 pins 27, which project horizontally from the

guide-tracks, they cause the upper edge of the lower section of the door to which the hooks are attached to be drawn inward against the wall, and the weight of the door in excess of the counterpoise is designed to be sufficient 70 to insure close locking of the door against the wall by this means. For securing the door in closed position against any attempt to open it any suitable locking device may be used to hold it down to the floor or hold it back 75 against the wall which will accomplish the same result.

I claim—

1. A warehouse-door comprising two sec- 80 tions hinged together at a horizontal longitudinal line and suspended hingewise by the upper side of the upper section, the lower section and the wall or casing to which the door shuts having one a hook and the other an ele- 85 ment for engaging the hook, the hook having the face for the encounter of the engaging element sloping inward downwardly for drawing the door in toward the wall as it approaches the limit of its descent.

2. A warehouse-door comprising two sec- 90 tions hinged together at a horizontal longitudinal line and suspended hingewise by the upper side of the upper section with a limited range of vertical movement at its said upper hinged side, the upper section of the door and 95 the wall or casing to which the door shuts having one a hook and the other an element for engaging the hook, the hook having the face for the encounter of the engaging element sloping inward downwardly for drawing the 100 upper section of the door inward toward the wall or casing as the door descends within the range of said vertical movement of its upper side.

3. A warehouse-door comprising two sec- 105 tions hinged together at a horizontal longitudinal line and suspended hingewise by the upper side of the upper section with a limited range of vertical movement at its said upper hinged side; an upwardly-open hook secured 110 to the wall or casing to which the door shuts and a stud projecting from the upper door-section overhanging said hook in position to encounter the same when said upper hinged side of the door descends, the face of said hook 115 so encountered being sloped downward inwardly for drawing the upper section of the door inward as it descends.

4. A warehouse-door comprising two sec- 120 tions hinged together at a horizontal longitudinal line and suspended hingewise by the upper side of the upper section with a limited range of vertical movement at said upper hinged side, the upper section of the door and the wall or casing to which it shuts having one 125 a hook and the other an element for engaging the hook in the descent of the door within said range of vertical movement of its upper side, the lower section of the door and the wall or casing having one a hook and the 130

other an element for engaging the hook as said lower section descends, the hooks having their respective faces which are encountered by the engaging elements sloping inward 5 downwardly for drawing said door-sections respectively inward toward the wall or casing in their descent.

5. A warehouse-door comprising two sections hinged together at a horizontal longitudinal line and suspended hingewise by the upper side of the upper section; means for guiding the lower side of the lower section vertically, said lower section, at a point above its vertically-guided lower side and the wall or 10 casing to which the door shuts, having one a hook and the other an element for engaging the hook, such hook having the face for encounter of the engaging element sloping inward downwardly for drawing the lower section 15 of the door inward toward the wall as it descends.

6. A warehouse-door comprising two sections hinged together at a horizontal longitudinal line and suspended hingewise by the upper side of the upper section and having a limited range of vertical movement at its said upper hinged side; means for guiding the lower side of the lower section vertically, said upper section and the wall or casing to which 20 the door shuts having one a hook and the other an element for engaging the hook, the element on the door-section overhanging the element on the wall or casing in position for encountering said element on the wall or casing 25 in the descent of the upper section of the door within the range of vertical movement of its said upper hinged side, the face of the hook for encounter with the engaging element being sloped inward downwardly for guiding the 30 door toward the wall or casing as it descends within said range of vertical movement of its upper hinged side.

7. A warehouse-door comprising two sections hinged together at horizontal longitudinal line, suspended hingewise by the upper side of the upper section and guided vertically at the lower side of the lower section and having limited range of vertical movement at its said upper hinged side, said upper and 45 lower sections, the former below and near to its upper hinged side and the latter above and near to its lower vertically-guided side, and the wall or casing to which the door shuts having co-operating elements for encounter and engagement as the door descends, one of the co-operating elements being a hook and the other a means for engaging the hook; the hook element having its face for encounter with the engaging element sloping downward inwardly 50 for guiding the door-sections inward as they descend after such encounter.

8. A warehouse-door comprising two sections hinged together at horizontal longitudinal line suspended hingewise by the upper

side of the upper section, and means for guiding the lower side of the lower section vertically, the pivot-line of the suspending-hinge at the upper side of the upper section being in a vertical plane outward with respect to the wall or casing from the pivot-line of the hinge between the two sections, the lower section, at a point above the means for guiding its lower edge, and the wall or casing to which the door shuts having one a hook and the other an element for engaging the hook as said 65 lower section descends, the hook having the face for the encounter of said hinged element sloping inward downwardly for drawing said lower element inward during the descent.

9. A warehouse-door comprising two sections hinged together at a longitudinal horizontal line suspended hingewise at the upper side of the upper section and having a limited range of vertical movement at its said upper hinged side; means for guiding the lower section vertically at the lower side, the pivot-line of the hinge by which the door is suspended at the upper side being in a vertical plane outward with respect to the wall to which the door shuts from the pivot-line of the hinge between the two sections, the upper section and the wall or casing to which the door shuts having one a hook and the other means for engaging the hook in the downward movement of said upper hinged side, the face of the hook 90 for encounter with the engaging element being sloped downward inwardly for guiding said upper section in toward the door-casing as it descends.

10. A warehouse-door comprising two sections hinged together at a horizontal longitudinal line and suspended hingewise by the upper side of the upper section with a limited range of vertical movement at said upper hinged side; means for guiding the lower section vertically at the lower side, the pivotal line of the hinge at which the upper section is suspended being outward with respect to the wall or casing from the pivot-line of the hinge of the two sections, the said upper and lower sections on the one hand and the wall or casing to which they are shut on the other hand having co-operating elements of which one is a hook and the other a means of engaging the hook as the sections respectively descend, the face of said hook for encounter with the engaging element being sloped downward inwardly to guide said sections inward to the wall or casing in their descent.

In testimony whereof I have hereunto set my hand, in the presence of two witnesses, at Chicago, Illinois, this 15th day of July, A. D. 1904.

JOHN ERWOOD.
